W. E. BROWN & L. C. GRANGER,
ARC LIGHT,
APPLICATION FILED SEPT. 15, 1911.

1,070,769.

Patented Aug. 19, 1913.

UNITED STATES PATENT OFFICE.

WILLIAM E. BROWN, OF MILWAUKEE, WISCONSIN, AND LEWIS C. GRANGER, OF TEKONSHA, MICHIGAN, ASSIGNORS OF ONE-THIRD TO WILLIAM M. STEWART, OF MILWAUKEE, WISCONSIN.

ARC-LIGHT.

1,070,769.

Specification of Letters Patent. Patented Aug. 19, 1913.

Application filed September 15, 1911. Serial No. 642,434.

To all whom it may concern:

Be it known that we, WILLIAM E. BROWN, a citizen of the United States, residing in Milwaukee, in the county of Milwaukee and

5 State of Wisconsin, and LEWIS C. GRANGER, a citizen of the United States, residing in Tekonsha, in the county of Calhoun and State of Michigan, have invented new and useful Improvements in Arc-Lights, of 10 which the following is a description, reference being had to the accompanying drawings, which are a part of this specification.

This invention has for its object to provide an arc light particularly designed for 15 use in the operation of moving picture machines, but capable of use generally.

A further object of the invention is to avoid the formation of a shadow in the projection from such arc light which is due to 20 carbons being arranged practically in alignment, and this shadow is obviated under the present invention by positioning the carbons at an angle to each other, preferably at an angle of 90 degrees.

25 Another object of this invention is to provide an arc light with the carbons disposed at an angle to each other and provided with means for independently adjusting the carbons toward or away from each other and 30 turning them to produce uniform consumption thereof.

With the above and other objects in view the invention consists in the arc light herein claimed and all equivalents.

35 Referring to the accompanying drawings in which like characters of reference indicate the same parts in different views: Figure 1 is a sectional elevation of an arc light constructed in accordance with this invention; and Fig. 2 is a sectional view thereof on the plane of line 2—2 of Fig. 1.

In these drawings 10 indicates a frame having a horizontal and a vertical portion substantially alike, the horizontal portion 45 having a pair of rings 11 and 12 formed thereon, the former having a shouldered insulating bushing 13 fitting therein, with a gear wheel 14 fixed on its projecting unshouldered end by means of a set screw, and 50 the ring 12 having an insulating bushing 15 fitting within it and containing a double flanged nut 16, with the flanges thereof engaging the bushing 15, and both held firmly in place within the ring 12 by means of a set 55 screw 17. The insulating sleeve 15 may be

formed in half sections to fit around the flange nut 16 between the flanges thereof, or one of the flanges of the nut may be turned up after the bushing is in place, though any desirable means for assembling the bushing on the nut between the flanges may be resorted to. The nut 16 has an arm 18 projecting from it and containing a binding post 19 to form one terminal of the lamp. A metal tube 20 is threaded within the nut 16 and has a key or feather 21 by which it is splined within the insulating bushing 13 so as to be rotated by the gear wheel 14 and fed longitudinally by its turning within the stationary nut. This metal tube 20 is split 70 at its front end and is tapered to fit within a tapering collar 22 threaded thereon, so that a carbon rod 23, which fits within the tube 20, may be tightly clamped by the co-operation of the tapering portions of the 75 collar 22 and the split end of the tube. A shaft 24 is journaled through the frame beneath the tube 20 and has a sleeve 25 loosely mounted thereon, carrying a gear wheel 26, meshing with the gear wheel 14, and an adjusting wheel 27, by means of which the parts may be turned, the wheel 26 being directly turned by the wheel 27 and serving to turn the gear wheel 14, with the consequent 80 turning and adjustment of the carbon. The shaft 24 also has an adjusting wheel 28 mounted on its rear end, and at its front end it is provided with a bevel gear 29, meshing with a bevel gear 30 on the upper end of a vertical shaft 31, which carries a 85 gear wheel 26' on its lower end corresponding with the gear wheel 26 for actuating a vertical carbon 23' through mechanism corresponding to the mechanism just described for operating carbon 23 and which mechanism has its parts designated by the same 90 reference characters, with the exception that they are primed.

95 From the foregoing it will be seen that the two carbons are adjustable independently from their respective adjusting wheels 27 and 28, and each is completely insulated from the rest of the mechanism. The operator is therefore enabled to adjust the carbons as desired, both by moving them longitudinally and by turning them to make their 100 consumption uniform.

105 In the ordinary arc lights for moving picture machines, the carbons are set in alignment with each other and slightly inclined. 110

This has been open to objection by reason of the fact that a shadow is produced which causes the picture to become light and dark in parts. By arranging the carbons at an angle to each other, with the horizontal positive carbon with its cavity or pit in position to turn its light directly to the condenser lens, the light is much more intense and is free from shadow.

10 The invention gives an ordinary light with 7 to 11 amperes, while the ordinary light for moving picture apparatus requires from 40 to 60 amperes.

15 It is not necessary that the carbons be directly at right angles to each other, for most any angle will do, but the nearer a right angle is approached the better the results are accomplished.

20 While the invention is particularly adapted for moving picture apparatus and spot lights, yet it may be utilized otherwise.

What we claim as new and desire to secure by Letters Patent, is:

25 1. An arc light, comprising a frame, insulating bushings fitting in the frame, a carbon holding tube having a threaded connection with one bushing and a feathered connection with the other bushing, one of the bushings being fixed in its position, on the 30 frame, and the other being rotatably mounted on the frame, and means for turning the rotatable bushing.

35 2. An arc light, comprising a frame, adjustable carbon holders thereon, arranged at approximately right angles to each other and each comprising insulating bushings mounted on the frame, one bushing being held stationary in the frame, a nut carried by the stationary insulating bushing, a binding post on said nut, a carbon holding tube

40 threaded through the nut and splined to the rotatable insulating bushing, a gear wheel on the rotatable insulating bushing, and an adjusting wheel having a driving connection with the gear wheel for turning the 45 same to cause the carbon holding tube to turn and adjust itself longitudinally through the nut.

3. An arc light, comprising a frame, carbon holders thereon, arranged at approximately right angles to each other and each comprising a pair of insulating bushings, one fixed within the frame and the other rotatable within the frame, a flanged nut contained within the fixed insulating bushing, a 50 carbon holding tube threaded through the nut and splined within the rotatable insulating bushing, a gear wheel carried by the rotary insulating bushing, and means for independently turning and adjusting the 55 carbon holders, comprising a shaft journaled through the frame, a sleeve mounted on the shaft, a gear wheel on the sleeve meshing with the gear wheel of one of the carbon 60 holders, an adjusting wheel on the sleeve, an adjusting wheel on the shaft, a second shaft journaled in the frame, gear connection between the two shafts, and a gear wheel on the second shaft meshing with the gear 65 wheel of the other carbon holder.

70 In testimony whereof, we affix our signatures, in presence of two witnesses.

WILLIAM E. BROWN.
LEWIS C. GRANGER.
